DOUBLE SOLVENT EXTRACTION OF TAR ACIDS

Martin B. Neuworth, Pittsburgh, Pa., assignor to Pittsburgh Consolidation Coal Company, Pittsburgh, Pa., a corporation of Pennsylvania

Application October 7, 1955, Serial No. 539,168

13 Claims. (Cl. 260—627)

This invention relates to the separation of organic compounds and more particularly to the double solvent extraction of dihydric phenols from a liquid mixture consisting essentially of high boiling monohydric and dihydric phenols.

Primarily, this invention is directed to the removal of color producing compounds found in the high boiling tar acid product resulting from the low temperature carbonization of coal, but this invention is equally applicable to the selective solvent extraction of dihydric phenols from any liquid mixture consisting essentially of high boiling monohydric phenols and dihydric phenols. This invention also is directed to the refining of tar acid oil and the separation and recovery of de-pinked tar acids from the tar acid oil.

Tar acids may be defined as phenols which are present in tar or tar distillates and are extractable with caustic soda solution. Tar acids do not consist so much of phenol itself as of homologues of the series such as cresols, xylenols and more complex phenol derivatives. The high boiling tar acids are the fraction boiling above 230° C. and are composed of both monohydric phenols and dihydric phenols. Some of the typical monohydric phenols are methyl ethyl phenol, polymethyl phenols, diethyl phenol and naphthol. Some of the typical dihydric phenols are pyrocatechol, resorcinol, hydroquinone and their alkylated derivatives. Throughout this specification the term "high boiling tar acids" will designate those tar acids boiling above about 230° C. and "low boiling tar acids" will designate those boiling below 230° C.

One of the outlets for high boiling tar acids is in the preparation of tar acid mixtures in an alkaline emulsion form for use as disinfectants. A factor that limits the marketability of the high boiling tar acids as disinfectants is the pink color of the alkaline emulsion which develops when the emulsion is exposed to air. It has been found that the coloring or pinking properties of the high boiling tar acids is due to the presence of various dihydric phenols in the emulsion. The removal of the dihydric phenols, or the elimination of the color producing properties of the high boiling tar acids is called de-pinking.

It is therefore the primary object of this invention to provide a process for de-pinking or removing the color-producing compound from the tar acids in a continuous solvent extraction process.

A further object of this invention is to provide a method of recovering the de-pinked tar acids from the solvent and recycling the solvent. Another object of this invention is to provide a process for removing dihydric phenols by solvent extraction from a mixture of high boiling monohydric phenols and dihydric phenols in a continuous process. Another object of this invention is to provide a process for refining tar acid oil and recovering de-pinked high boiling tar acids from the tar acid oil in a continuous process.

Many methods have been proposed for either de-pinking tar acids or removing dihydric phenols from a mix-

ture of monohydric phenols and dihydric phenols. The prior methods, however, are unsatisfactory for various reasons. Some methods, such as the air blowing treatment of tar acids, destroy valuable monohydric phenols along with the color-producing dihydric phenols. Other methods, such as the water extraction treatment of tar acids, only partially remove the color producing dihydric phenols and hence do not satisfactorily de-pink the tar acids. The chemical treatment of tar acids with sodium tetraborate, buffer agents and the like are expensive to operate and require elaborate process equipment.

In accordance with my invention I have discovered that by contacting the tar acids with a paraffinic naphtha solvent and an aqueous methanol solvent the color producing dihydric phenols may be separated from the high boiling tar acids. The color producing dihydric phenols are removed as extracts in the aqueous methanol phase while the de-pinked tar acids are removed in the paraffinic naphtha phase.

More specifically, the tar acids are fed into a double solvent countercurrent extraction column at a point between the two solvent feed points. Since the high boiling tar acids have a high viscosity at room temperature, they may be treated to lower their viscosity before entering the extraction column. Any conventional method of lowering the viscosity of the high boiling tar acids may be used, however, I prefer to dissolve the tar acid feedstock in a naphtha solvent to lower its viscosity. As the tar acids are fed into the extraction column aqueous methanol is fed into the top portion of the extraction column and a naphtha solvent is fed into the bottom of the column. The tar acids are contacted with both the aqueous methanol and the naphtha solvent which pass through the column in countercurrent relation. The aqueous methanol strips out the color-producing dihydric phenols which are removed in the aqueous methanol solution from the bottom of the column; the de-pinked tar acids dissolve in the naphtha solvent and are removed in the naphtha solution from the top of the column.

At atmospheric pressure and normal temperature the aqueous methanol solvent should contain about 30 to 40 percent by weight methanol. I have discovered that at these conditions of temperature and pressure, an aqueous methanol solution containing either less than 30 percent methanol or more than 40 percent methanol result in the formation of three liquid phases. The composition of the three phases formed is not known, however, their formation prevents the extraction type of separation.

The results of this invention are surprising in view of the results obtained and disclosed in U. S. Patent 2,666,796 of which I am a copatentee, wherein a process is described for extracting tar acids from neutral oils by solvent extraction using as solvents paraffinic naphtha and aqueous methanol of 55 to 75 percent concentration.

As shown in this patent, the naphtha raffinate contains the neutral oils and the aqueous methanol extract contains the tar acids. Now I have discovered by changing the concentration of the aqueous methanol solvent, the monohydric tar acids which are rejected from the naphtha phase in the above mentioned patent process, can be dissolved in the naphtha solvent.

For the naphtha solvent I prefer to use a paraffinic distillate obtained from petroleum. The naphtha density should be less than 0.80 and preferably less than 0.75 to insure sufficient gravity difference between the two phases in the extraction column to effect a ready separation of the phases. The hexane cut of a paraffinic distillate combines all these critical properties and accordingly is preferred as the solvent in this invention.

For a clear understanding of my invention, its objects and advantages, reference should be had to the following detailed description and accompanying drawing which

is a diagrammatic illustration of apparatus adapted to treat tar acid oil derived from low temperature carbonization of bituminous coal to produce a neutral oil product, a low boiling tar acids product, a de-pinked high boiling tar acid product and a dihydric phenol product.

Referring to the drawing, tar acid oil is pumped from a storage tank 10 continuously through a pipeline 12 into the central portion of a continuous countercurrent double solvent center feed extraction column 14. The extraction column may be of an convenient design capable of providing a sufficient number of theoretical extraction stages to effect the desired separation of tar acids from the tar acid oil. A conventional packed tower may be used, for example, as well as a pierced plate column, a bubble cap column, a rotating disc column or a column containing alternate zones of quiescence and turbulence.

Aqueous methanol solution is fed continuously from a methanol storage tank 16 through a pipeline 18 into the top of the extraction column 14. A mixing valve 20 is positioned in the line 18 and water enters the mixing valve 20 through a pipeline 22. The mixing valve 20 regulates the concentration of aqueous methanol so that an aqueous methanol solution containing from 55 to 75 percent by weight of methanol enters the extraction column 14. Naphtha is fed continuously from a naphtha storage tank 24 through a pipeline 26 into the bottom of the extraction column 14.

Since the density of the aqueous methanol solution exceeds the density of the naphtha, the aqueous methanol solution descends through the column and dissolves tar acids while the lighter naphtha passes countercurrently upward through the column and dissolves the neutral oils contained in the tar acid oil feed.

Aqueous methanol extract containing purified recovered tar acids, is withdrawn continuously from the bottom of the extraction column 14 through a pipeline 28 and fed into a stripper or distillation column 30.

The tar acids and water solution leave the stripper 30 and pass through a cooler 32 which aids in the phase separation of the water from the tar acids. The tar acid and water mixture leaves the cooler 32 through a pipeline 34 and enters a phase separation tank 36. The purified tar acids leave the separation tank 36 through a pipeline 38 and enter a fractionation column 40.

Anhydrous methanol passes overhead from the stripper 30 through pipeline 42 to a reflux condenser 44 and passes through a pipeline 46 to the aqueous methanol storage tank 16. A portion of the condensed methanol may be returned through a pipeline 48 to the top of the stripper 30 as reflux.

Naphtha with dissolved neutral oil leaves the top of the extraction column 14 through a pipeline 50 and passes to a distillation column or stripper 52 where the naphtha is separated from the neutral oil. Naphtha passes overhead from the stripper 52 through a pipeline 54 and reflux condenser 56. A portion of the naphtha may be recirculated through a pipeline 58 as reflux for the stripper 52. The naphtha leaves the reflux condenser 56 and returns through a pipeline 60 to the naphtha storage tank 24. The neutral oil leaves the stripper 52 as the bottom product through pipeline 62.

Water leaves the decanter or phase separation tank 36 through the pipeline 63 and passes to the methanol storage tank 16. The tar acids which are withdrawn from the bottom of the phase separator tank 36 are substantially free of neutral hydrocarbons and pass through the pipeline 38 to the fractionating tower 49 where the tar acids are separated into two fractions. The fraction boiling below 230° C. leaves the top of the fractionating tower as distillate through a pipeline 64 and is conveyed to either storage or further processing facilities. The tar acids boiling above 230° C. leave the fractionating tower 49 as bottoms and pass through a pipeline 66 and enter a mixing tank 68. Naphtha solvent is pumped through a pipeline 70 into the mixing tank 68 where it is mixed

5 with the high boiling tar acids in a ratio of about one-half volume of naphtha solvent for each volume of tar acids. The naphtha solvent is mixed with the tar acids at this point to lower the viscosity of the tar acids prior to their entering a countercurrent extraction column 72. The tar acids and naphtha mixture is pumped through a pipeline 74 into the continuous countercurrent double solvent center feed extraction column 72. The extraction column 72 is similar to the extraction column 14 and may be of any convenient design capable of providing a sufficient number of theoretical extraction stages to effect the desired separation of the color producing dihydric phenols from the tar acids.

15 Aqueous methanol solution is fed continuously from the aqueous methanol storage tank 16 through a pipeline 76 into the top of the extraction column 72. A mixing valve 78 is positioned in the pipeline 76. Water is conducted through a pipeline 80 into the mixing valve 78 where it is mixed with the methanol from the methanol storage tank 16 so that the aqueous methanol solvent contains between 36 to 40 percent by weight methanol. Naphtha is fed continuously from the naphtha storage tank 24 through a pipeline 82 into the bottom of the extraction column 72.

20 Since the aqueous methanol solution has a greater density than the naphtha, the aqueous methanol entering the extraction column 72 through the pipeline 76 will descend through the extraction column 72 and dissolve the color producing dihydric phenols while the naphtha solution passes countercurrently upward through the column and dissolves the remaining tar acids.

25 The preferred rates of feed of the tar acids and the aqueous methanol and naphtha solvents are four to six volumes of aqueous methanol and two to three volumes of naphtha for each volume of tar acids. It should be understood, however, when the tar acids are treated with naphtha before entering the extraction column, the rate of naphtha feed in the column will be proportionately decreased to maintain the preferred ratios.

30 The aqueous methanol extract containing the color producing dihydric phenols is withdrawn continuously from the bottom of the extraction column 72 through a pipeline 84 and fed into a distillation column or stripper 86. In the stripper 86 the methanol solvent is separated from the water and color producing dihydric phenols. The mixture of water and color producing dihydric phenols mixture leaves the stripper 86 as bottoms through a pipeline 88 for further treatment or storage.

35 Anhydrous methanol passes overhead from the stripper 86 through a pipeline 90 into a reflux condenser 92. The anhydrous methanol leaves the reflux condenser 92 through a pipeline 94 which conveys the anhydrous methanol to the aqueous methanol storage tank 16. The stripper 86 is provided with a reflux pipeline 96 which is operable to return a portion of the condensed methanol to the stripper 86 as a reflux.

40 Naptha solvent containing de-pinked, dissolved tar acids leaves the top of the extraction column 72 through a pipeline 98 and passes to a distillation column or stripper 100 where the naphtha is separated from the de-pinked tar acids. The de-pinked tar acids leave the stripper 100 as bottoms through a pipeline 102 and are pumped to storage or further processing facilities. The naphtha passes overhead from the stripper 100 through a pipeline 104 and enters a reflux condenser 106. The naphtha which leaves the reflux condenser 106 enters a pipeline 108 and is conveyed to the naphtha storage tank 24. A pipeline 110 is connected to the pipeline 106 and the stripper 100 and is operable to return a portion of the naphtha as reflux for the stripper 100.

45 A tank 112 supplies additional make-up methanol through the pipeline 114 to the aqueous methanol storage tank 16. Although the mixing valves 20 and 78 are shown diagrammatically, it should be understood that the valves 20 and 78 are the equivalent of any means operable

to regulate the concentration of the methanol solution so that the methanol solution will be of proper methanol concentration to effect separation in the respective extraction columns 14 and 72.

EXAMPLES

To illustrate the present process, a quantity of tar produced by low temperature carbonization of bituminous coal was recovered and topped to 350° C. The topped tar was separated into a first fraction containing neutral oils and a second fraction containing tar acids by the process described in U. S. Patent 2,666,796 above-mentioned. The resulting tar acids fraction was fractionated into a distillate containing tar acids boiling below 230° C. and a second fraction containing tar acids boiling from 230° to 350° C., so-called high boiling tar acids.

These high boiling tar acids were subjected to a standard pinking test to determine whether color producing dihydric phenols were present. The test comprises mixing the tar acids with a solution of 10% sodium hydroxide and then air blowing the mixture. After a short period of the air blowing, tar acids which contain color producing dihydric phenols will exhibit a characteristic pink color. The tar acids used in these examples exhibited the pink color, indicating presence of dihydric phenols.

The tar acids used in these examples were diluted with one-half volume of hexane for every volume of tar acid. This dilution lowered the viscosity of the tar acids so that the mixture could be easily introduced into the center of an extraction column at normal pressure and temperature. The extraction column was one inch in diameter, eight feet long and contained twenty-eight turbulent zones alternately disposed between twenty-nine calming zones. Aqueous methanol solvent was fed into the top of the extraction column; a commercial hexane solvent was fed into the bottom of the extraction column and maintained as the continuous phase. In the following tables are tabulated processing conditions and results from these runs for removing the color producing dihydric phenols from high boiling tar acids.

Table

Run designation	A 30%	B 35%	C 40%
Concentration of aqueous methanol			
Feed rates (volumes):			
Tar acids hexane mixture	4.5	4.5	4.5
Aqueous methanol	12.0	12.0	18.0
Hexane	10.5	10.5	10.5
Yields (wt. percent of tar acids in feed):			
Aqueous methanol extract	11	12	21
Hexane raffinate	89	88	79

To determine the pinking properties of the tar acids in the hexane raffinate, the hexane was first removed by distillation. The remaining tar acids were then selectively distilled and fractions boiling at 10° intervals were subjected to the pinking test.

In run A the tar acids from the hexane raffinate boiling between 230° C. and 260° C. did not turn pink when subjected to the pinking test whereas the tar acids boiling between 260° C. and 350° C. did turn pink under the same testing conditions. The results of these tests on run A indicate that all of the color producing dihydric phenols are removed from the tar acids boiling between 230° C. and 260° C. when aqueous methanol having a concentration of 30 weight percent of methanol is used.

In run B the tar acids from the hexane raffinate boiling between 230° C. and 280° C. failed to turn pink when subjected to the pinking test whereas the tar acids boiling between 280° C. and 350° C. did turn pink under the same testing conditions. These test results on run B indicate that all the color producing dihydric phenols are removed from the tar acids boiling between 230° C. and 280° C. when aqueous methanol having a concentration of 35 weight percent methanol is used.

In run C the tar acids in the hexane raffinate boiling

75

between 230° C. and 300° C. failed to turn pink when subjected to the pinking tests whereas the residue boiling above 300° C. discolored when subjected to the same test. These test results on run C indicate that all the color producing dihydric phenols are removed from the tar acids boiling between 230° C. and 300° C. when aqueous methanol having a concentration of 40 weight percent methanol is used.

To determine the pinking properties of the tar acids in the aqueous methanol extract the methanol was first removed by distillation. The remaining tar acids were selectively distilled and subjected to the pinking tests. In all of the runs the tar acids of the aqueous methanol extract turned pink when subjected to the pinking test, thus indicating the presence of the color producing dihydric phenols in the aqueous methanol extract.

Thus it will be seen according to the above table that color producing dihydric phenols can be separated from high boiling tar acids by means of the present invention and that high yields of de-pinked tar acids can be obtained. In run A, the yield of tar acids in the hexane raffinate is 89 percent and a cut of the tar acids boiling between 230° C. and 260° C. has been completely de-pinked. In run C the tar acids yield is 79%; however, in conjunction with this slightly lower yield, a fraction of tar acids boiling between 230° C. and 300° C. has been completely de-pinked.

Thus there is a relatively complete de-pinking of the tar acids with the concentration of methanol at 40 weight percent.

The examples also illustrate the selective extraction of color producing dihydric phenols from various cuts of high boiling tar acids. Thus if a product having a boiling range between 230° C. and 280° C. is desired and it is desired to de-pink the tar acids in this product the proper methanol concentration would be 35% and the hexane raffinate would contain 88% of the tar acid feed mixture. Of this 88% all of the product boiling between 230° C. and 280° C. would be free of color producing dihydric phenols. This is shown in run B.

According to the present invention, therefore, it is now possible to extract color producing dihydric phenols from high boiling tar acids and also it is now possible to selectively extract color producing dihydric phenols from certain pre-determined cuts of high boiling tar acids.

According to the provisions of the patent statutes, I have explained the principle, preferred construction and mode of operation of my invention and have illustrated and described what I now consider to represent its best embodiment. However, I desire to have it understood that, within the scope of the appended claims, the invention may be practiced otherwise than as specifically illustrated and described.

I claim:

1. A process for extracting de-pinked tar acids from a tar acid oil fraction obtained from low temperature carbonization of bituminous coal which comprises the steps of feeding said tar acid oil into a vertical extraction zone, feeding a solvent consisting essentially of a paraffinic naphtha fraction boiling within the range of 60° to 130° C. and having a density of less than 0.8 into the bottom of said extraction zone, feeding a second solvent consisting essentially of an aqueous methanol solution containing 55 to 75 weight percent methanol and the balance water into the top of said extraction zone, passing said naphtha through said extraction zone countercurrently to and in intimate contact with said aqueous methanol solution, recovering an aqueous methanol extract containing tar acids from the bottom of said vertical extraction zone, passing said aqueous methanol extract into a first distillation zone, separating the methanol from the tar acids and water in said first distillation zone, recovering a mixture of tar acids and water from said first distillation zone, recovering the tar acids

from the mixture of tar acids and water by phase separation, passing thus separated tar acids into a second distillation zone, recovering those high boiling tar acids boiling above 230° C. from said second distillation zone substantially free of neutral hydrocarbons, mixing said high boiling tar acids with paraffinic naphtha, feeding said treated high boiling tar acids into a second extraction zone, feeding a third solvent consisting essentially of paraffinic naphtha having a density of 0.8 into the bottom of said second extraction zone, feeding a fourth solvent consisting essentially of an aqueous methanol solution containing about 30 to 40 percent by weight methanol and the balance water into the top of said second extraction zone, passing said naphtha through said extraction zone countercurrently to and in intimate contact with said aqueous methanol solution, maintaining said third solvent as the continuous phase in said second extraction zone, regulating the ratios of said solvents to maintain a two liquid phase system within said extraction zone, and recovering a naphtha raffinate containing the de-pinked high boiling tar acids.

2. An extraction process for separating dihydric phenols from a mixture consisting essentially of monohydric phenols and dihydric phenols that boil above 230° C. which comprises feeding said mixture into an extraction zone, feeding a solvent consisting essentially of paraffinic naphtha having a density of less than 0.8 into said extraction zone, feeding a second solvent consisting essentially of an aqueous methanol solution containing about 30 to 40 percent by weight methanol and the balance water into said extraction zone, passing said naphtha through said extraction zone countercurrently to and in intimate contact with said aqueous methanol solution, regulating the ratios of said solvents to maintain a two liquid phase system within said extraction zone, and recovering an aqueous methanol extract containing dihydric phenols and a naphtha raffinate from said extraction zone.

3. An extraction process for separating dihydric phenols and monohydric phenols from a mixture consisting essentially of monohydric phenols and dihydric phenols that boil above 230° C. which comprises mixing said mixture with paraffinic naphtha, feeding the treated mixture into a vertical countercurrent extraction zone, feeding a solvent consisting essentially of paraffinic naphtha having a density of less than 0.8 into the bottom of said extraction zone, feeding a second solvent consisting essentially of an aqueous methanol solution containing about 30 to 40 percent by weight methanol and the balance water into the top of said extraction zone, passing said naphtha through said extraction zone countercurrently to and in intimate contact with said aqueous methanol solution, regulating the ratios of said solvents to maintain a two liquid phase system within said extraction zone, and recovering an aqueous methanol extract containing dihydric phenols.

4. The process of claim 3 in which the naphtha is the continuous phase in said extraction zone.

5. An extraction process for separating dihydric phenols and monohydric phenols contained in a mixture consisting essentially of monohydric phenols and dihydric phenols that boil above 230° C., which comprises the steps of feeding said mixture into a vertical countercurrent extraction zone, feeding a solvent consisting essentially of paraffinic naphtha having a density of less than 0.8 into the bottom of said extraction zone, feeding a second solvent consisting essentially of an aqueous methanol solution containing 30 to 40 percent by weight of methanol and the balance water into the top of said extraction zone, passing said naphtha through said extraction zone countercurrently to and in intimate contact with said aqueous methanol solution, regulating the ratios of said solvents to maintain a two liquid phase system within said extraction zone, and recovering aqueous methanol extract con-

taining dihydric phenols from the bottom of said extraction zone.

6. An extraction process for separating dihydric phenols and monohydric phenols contained in a mixture of high boiling phenols consisting essentially of monohydric phenols and dihydric phenols that boil above 230° C., which comprises preparing a solution of said mixture in paraffinic naphtha, feeding said solution into a vertical countercurrent extraction zone, feeding a solvent consisting essentially of paraffinic naphtha having a density of less than 0.8 into the bottom of said extraction zone, feeding a second solvent consisting essentially of an aqueous methanol solution containing 30 to 40 percent by weight methanol and the balance water into the top of said extraction zone, passing said naphtha through said extraction zone countercurrently to and in intimate contact with said aqueous methanol solution, regulating the ratios of said solvents to maintain a two liquid phase system within said extraction zone, and recovering an aqueous methanol extract containing said dihydric phenols from the bottom of said vertical extraction zone and a naphtha raffinate from the top of said vertical extraction zone.

7. The process of claim 6 in which methanol is separated from the aqueous methanol extract by distillation and recirculated in said extraction zone and that portion of the aqueous methanol extract remaining after removal of the methanol is separately recovered and the naphtha is separated from the naphtha raffinate by distillation and recirculated in said extraction zone and that portion of the naphtha raffinate remaining after removal of the naphtha is separately recovered.

8. The process of claim 6 in which the naphtha solvent is a hexane cut of petroleum naphtha.

9. An extraction process for separating the color producing dihydric phenols from a mixture consisting essentially of monohydric phenols and dihydric phenols obtained from a distillate fraction of the tar produced by the low temperature carbonization of bituminous coal, which comprises feeding that portion of said mixture of monohydric phenols and dihydric phenols boiling above 230° C. into a vertical countercurrent extraction zone, feeding a solvent consisting essentially of paraffinic naphtha having a density of less than 0.8 into the bottom of said extraction zone, feeding a second solvent consisting essentially of an aqueous methanol solution containing 30 to 40 percent by weight of methanol and the balance water into the top of said extraction zone, passing said naphtha through said extraction zone countercurrently to and in intimate contact with said aqueous methanol solution, regulating the ratios of said solvents to maintain a two liquid phase system within said extraction zone, and recovering from said extraction zone an aqueous methanol extract containing the color producing dihydric phenols and a naphtha solution containing monohydric phenols.

10. A selective extraction process for separating color producing dihydric phenols and monohydric phenols, contained in a mixture of high boiling phenols consisting essentially of monohydric phenols and dihydric phenols that boil above 230° C., which comprises the steps of feeding said mixture into a vertical countercurrent extraction zone, feeding a solvent consisting essentially of paraffinic naphtha having a density of less than 0.8 into the bottom of said extraction zone, feeding a second solvent consisting of an aqueous methanol solution containing about 30 to 40 percent by weight of methanol and the balance water into the top of said extraction zone, passing said naphtha through said extraction zone countercurrently to and in intimate contact with said aqueous methanol solution, regulating the ratios of said solvents to maintain a two liquid phase system within said extraction zone, and recovering a naphtha raffinate containing de-pinked phenols boiling between 230° C. and 260° C. from the bottom of said extraction zone.

11. An extraction process for separating the color pro-

ducing dihydric phenols from a mixture consisting essentially of monohydric phenols and dihydric phenols boiling above 230° C., which comprises the steps of feeding said mixture into a vertical countercurrent extraction zone, feeding a solvent consisting essentially of paraffinic naphtha having a density of less than 0.8 in to the bottom of said extraction zone, feeding a second solvent consisting essentially of an aqueous methanol solution containing about 35 to 40 percent by weight of methanol and the balance water into the top of said extraction zone, passing said naphtha through said extraction zone countercurrently to and in intimate contact with said aqueous methanol solution, regulating the ratios of said solvents to maintain a two liquid phase system within said extraction zone, and recovering a naphtha raffinate containing de-pinked phenols boiling between 230° C. and 280° C. from the bottom of said extraction zone.

12. A method of extracting color producing phenolic constituents from high boiling tar acids consisting essentially of monohydric phenols and dihydric phenols that boil above 230° C. which comprises feeding the tar acids containing the color producing constituents into a vertical countercurrent extraction zone, feeding a solvent consisting essentially of paraffinic naphtha having a density of less than 0.8 into the bottom of said extraction zone, feeding a second solvent consisting essentially of an aqueous methanol solution containing about 30 to 40 percent by weight methanol and the balance water into the top of said extraction zone, passing said naphtha through said extraction zone countercurrently to and in intimate contact with said aqueous methanol solution, regulating the ratios of said solvents to maintain a two liquid phase system within said extraction zone, and recovering a naphtha raffinate from said extraction zone containing said tar acids free from color producing phenolic constituents.

13. A process for extracting de-pinked tar acids from a tar acid oil fraction obtained from low temperature carbonization of bituminous coal which comprises the steps of feeding said tar acid oil into a vertical extraction zone,

feeding a solvent consisting essentially of a paraffinic naphtha fraction boiling within the range of 60° to 130° C. and having a density of less than 0.8 into the bottom of said extraction zone, feeding a second solvent consisting essentially of an aqueous methanol solution containing 55 to 75 weight percent methanol and the balance water into the top of said extraction zone, passing said naphtha through said extraction zone countercurrently to and in intimate contact with said aqueous methanol solution, recovering an aqueous methanol extract containing tar acids from the bottom of said vertical extraction zone, passing said aqueous methanol extract into a distillation zone, separating the methanol from the tar acids and water in said extraction zone, recovering the mixture of tar acids and water from the bottom of said distillation zone, recovering the tar acids from the mixture of tar acids and water by phase separation, passing said tar acids into a second distillation zone, recovering those high boiling tar acids boiling above 230° C. from the bottom of said second distillation zone substantially free of neutral hydrocarbons, feeding said treated high boiling tar acids into a second extraction zone, feeding a third solvent consisting essentially of paraffinic naphtha having a density of 0.8 into the bottom of said second extraction zone, feeding a fourth solvent consisting essentially of an aqueous methanol solution containing about 30 to 40 percent by weight methanol and the balance water into the top of said second extraction zone, passing said naphtha through said extraction zone countercurrently to and in intimate contact with said aqueous methanol solution, regulating the ratios of said solvents to maintain a two liquid phase system within said extraction zone, and recovering a naphtha raffinate containing the de-pinked high boiling tar acids.
